UNITED STATES PATENT OFFICE.

ELMER E. WALTER, OF CHICAGO, ILLINOIS.

PIANO.

No. 888,209.

Specification of Letters Patent.

Patented May 19, 1908.

Application filed April 8, 1907. Serial No. 367,001.

To all whom it may concern:

Be it known that I, ELMER E. WALTER, a citizen of the United States, residing in Chicago, in the county of Cook and State of Illinois, have invented certain new and useful improvements in Pianos, of which the following is a specification.

My invention relates in general to pianos, and particularly to piano casings.

10 At the present time piano casings are universally made of wood coated with a varnish finish. As both wood and varnish are injuriously affected by moisture and by changes in temperature, a large majority of the defects in and objections to pianos are to the casings, as the sound-producing mechanism has been so perfected as to give rise to little trouble. The varnish checks or cracks when subjected to atmospheric changes, and 15 blisters when exposed to heat. The wood shrinks when heated, and swells when too moist, thereby cracking the finish. In order to reduce as far as possible injuries to the casings, a great deal of time is expended in 20 their manufacture—in properly seasoning the wood and applying the finish.

The primary object of my invention is to provide a casing for pianos, and similar musical instruments, which will be attractive in 30 appearance and at the same time free from the objections incident to varnish-finished wood casings.

A further object of my invention is to provide a piano casing which will be simple, and 35 at the same time strong and durable in construction, which may be quickly and economically manufactured, and the attractiveness of the appearance of which will not be impaired either by changes in temperature or 40 atmospheric conditions.

My invention may be generally described as consisting of an attractively finished piano casing comprising a pressed sheet metal front, a sheet metal top, and a sheet metal 45 back frame composed of top and bottom rails united by posts formed of sheet metal.

My invention will be more fully described hereinafter with reference to the accompanying drawings, in which the same is illustrated 50 as embodied in a convenient and practical form, and in which

Figure 1 is a rear elevational view; Fig. 2 a vertical sectional view at the middle of the keyboard; Fig. 3 an enlarged vertical sectional view, taken on line 3—3 of Fig. 1

through the back of the casing, and showing the usual pin-block supported thereby; Fig. 4 an end elevational view; and Figs. 5 and 6 perspective detail views of one of the posts of the back of the casing.

60 The same reference characters are used to designate the same parts in the several figures of the drawings.

Reference character A designates the upper portion of the front of the casing, while reference letter B designates the fall board.

Reference letter C indicates the key-bed, and D the bottom front board.

E designates one of the posts interposed between the keyboard and the toe F.

The above parts, composing the front of the casing, are made of sheet metal, preferably sheet steel, pressed by suitable dies to impart any desired ornamental appearance thereto.

70 Reference characters G' and G² designate the side walls of the casing, while reference character G indicates the top of the casing, which may be conveniently hinged at its rear edge to the adjacent edge of the angular top rail H' of the back of the casing. The top rail H' is secured to the upper ends of vertical posts H, the lower ends of such posts being secured to the bottom rail H² of the back of the casing. The posts H are made 80 of sheet metal, preferably bent into channel form, the upper ends of the side flanges of the channel being bent inwardly to support the usual pin block K. The upper ends of the posts are preferably offset inwardly, as 85 indicated by the reference character h' so as to underlie the top rail H', while the lower ends of the posts are also offset inwardly as indicated by the reference character h² to underlie the bottom rail H², thereby permitting 90 the outer surfaces of the posts to lie flush with the surfaces of the top and bottom rails. The upward projecting ends h² of the posts H are riveted to the horizontal angle-iron rail k, within which is supported the 95 pin block K.

100 The sheet metal casing may be coated with any desired finish, and as such finish may be baked, it is not cracked by the changes in temperature, and being upon metal it is not subjected to injury, as is the case when the finish is upon wood, which expands and contracts as the atmospheric conditions vary.

105 By constructing a piano casing of metal in the manner above described, the tone of the 110

instrument is not injuriously affected, while the appearance of the casing is improved and it is rendered more durable.

From the foregoing description, it will be observed that I have invented an improved piano casing, which is simple, efficient and economical in construction, can be made in a comparatively short time, and will have a permanently attractive appearance. It will be further evident that by my improved casing the weight of a piano is lessened and the handling of it rendered less difficult, while at the same time its strength is increased.

Having now fully described my invention, what I claim as new and desire to secure by Letters Patent is:

1. In a piano casing, a pressed sheet metal front, a metal back frame comprising top and bottom rails, posts connecting said rails, and a pin block, the said top rail extending continuously above and behind the said pin block.

2. A piano casing comprising sheet metal top and side walls, an angular metal rear rail

near the top, a pin block supported within said rail, an angular metal rear bottom rail, sheet metal posts interposed between said rails and having flanges adjacent the upper ends thereof upon which the said first mentioned rail rests.

3. In a piano casing, the combination with a pressed sheet metal front, of a sheet metal back frame comprising top and bottom rails, posts connecting said rails, the upper ends of said posts having flanges, and a pin block supported within the top rail upon said flanges.

4. A piano casing, comprising a pressed sheet metal front, sheet metal side walls, a back frame having top and bottom metal horizontal members with vertical metal members extending between them, and a pin block inclosed above and behind by said top horizontal member.

ELMER E. WALTER.
